ELECTROMAGNETIC SQUARE WAVE
PRODUCING DEVICE

Albert E. Feinberg, Chicago, Ill., assignor to Advance
Transformer Co., Chicago, Ill., a corporation of Illinois
Filed Nov. 14, 1952, Ser. No. 320,470
18 Claims. (Cl. 315—254)

This invention relates generally to transformers and more particularly is concerned with a transformer of the character which when energized will produce a substantially square or clipped wave.

In the electrical lighting industry, high leakage reactance transformers are used to provide the necessary ballast in the use of gaseous discharge devices such as fluorescent lamps, gaseous discharge tubes and the like. It is required at times that a device in a circuit draw leading current. Under such circumstances, the transformer must provide, in addition to the high leakage reactance between the primary and the secondary serving the leading gaseous discharge device, means to produce additional leakage reactance at a point in the magnetic circuit in common with both the primary and the leading secondary windings in order to prevent saturation in the magnetic core. In the case of a simple transformer for use with a single gaseous discharge device, this may take the form of a non-magnetic gap at the end of the common magnetic leg. This type of structure is also found advantageous in the case of lagging secondaries, but the likelihood of saturation is not as great.

For example, in a shell type of transformer in which there is a rectangular frame-like portion and a central longitudinal winding leg having the winding disposed thereon, the two windings are separated by a magnetic shunt including air gaps, and the end of the winding leg adjacent the secondary winding is also provided with an air gap. This produces leakage reactance which is common to both the primary and the secondary magnetizing fluxes. The construction as described prevents saturation in the core in the vicinity of the secondary winding, which is an undesirable characteristic of secondaries drawing leading current.

Mechanically, it is practically necessary that there be at least a very small bridging projection or protuberance on one or the other of the juxtaposed faces of the gap. This protuberance is needed for support and to prevent the chattering or buzzing which may be caused by such structures. It has been found, however, that such structures, while providing current that is fairly sinusoidal, nevertheless cause an undesirable type of distortion characterized by a very sharp peak of high amplitude superimposed on the resulting voltage wave. Two important disadvantages arise by virtue of this peak. In the first place, the sharp peak is to some extent reflected in the current wave and decreases lighting efficiency. In the second place, in the type of gaseous discharge device which is required to be preheated before ignition, such peaking of the voltage wave will give rise to pre-ignition. Under these circumstances, the filaments of such devices will be bombarded by heavy ions during the time that their emitting faculties are being built up, thereby shortening the life of such filaments.

I believe that the peaking is caused by a sudden increase in the permeability of the small bridging connection or protuberance at the top of the voltage wave giving rise to a surge or sudden increase in the rate of change of flux. The voltage in a device of this kind lags the instantaneous magnetic flux and the magnetizing current by 90° and is proportional to the rate of change of flux. Thus when the flux wave passes through zero, the voltage is a maximum, i.e., reaches its peak. Likewise, when

2

the flux wave is at a maximum, the voltage is zero. In a constricted flux path such as this small bridging projection or protuberance, the permeability of the area will be large when the flux is near zero (and the voltage maximum) and the permeability will drop practically to that of the surrounding air space due to its saturation when the flux increases at zero voltage. Now, as the flux decreases toward zero, the permeability of the restricted area will continue to increase until it will be very great near zero flux. At this point the flux will suddenly increase rapidly in the opposite direction until the constricted area is once more saturated and the reluctance of that path approaches that of the air space surrounding this area. As the voltage decreases from that point onward, the flux will continue to increase but at a slower rate. Obviously then, this would cause the peak at the crest of the voltage wave, because the flux rate of change at the zero point suddenly increases.

This invention, therefore, has as a principal object 20 thereof the elimination of the peaked voltage wave from the electromagnetic structure of character described wherein the secondary may be carrying a leading current.

A further object of the invention is the provision of 25 a novel electromagnetic device which will produce a generally square current wave in the secondary thereof, whereby when used with gaseous discharge devices providing illumination, greater lighting efficiency will be obtained.

Still another object of the invention is to provide a 30 transformer of the character described in which the magnetic high leakage reactance shunt between the primary and secondary windings is provided with highly constricted bridging portions whereby to offset and overcome the tendency of the leading secondary to produce peaked crest current waves.

A still further object of the invention is to provide a 35 transformer which will produce a generally square or clipped voltage wave and is capable of delivering a current of like wave shape to a load.

Many other objects will occur to those skilled in the 40 art to which the invention appertains, but all within the purview and scope of the invention. For the purpose of complying with the patent statutes I have illustrated preferred embodiments of the invention which, 45 when considered in connection with the description will clearly demonstrate the advance that I have made in the arts and sciences.

In the drawings:

FIG. 1 is semi-diagrammatic view generally in section 50 showing the construction of a transformer or the like of the kind to which the invention may be applied, illustrating prior constructions.

FIG. 2 is a schematic electrical diagram of a circuit 55 utilizing the device of FIG. 1 for the ignition and operation of a gaseous discharge tube for lighting purposes.

FIG. 3 is a fragmentary view of the end of a device 60 of the type shown in FIG. 1 but having a modified form of the prior construction.

FIG. 4 is a diagrammatic representation of the voltage 65 wave produced in the secondary of the device of FIG. 1 or FIG. 3, showing the peaked crests.

FIG. 5 is a semi-diagrammatic view generally in section similar to that of FIG. 1 but showing the construction 70 of the invention.

FIGS. 6, 7 and 8 are fragmentary views of the center 75 of a transformer or other magnetic device similar to that of FIG. 5 but showing modified forms of the invention.

FIGS. 9 and 10 are diagrammatic representations of 80 voltage waves produced in the secondaries of the devices of FIGS. 5 to 8 inclusive and showing the manner in

which the crests of the waves are flattened because of the invention.

In FIG. 1 there is illustrated a transformer of the general type with which we are concerned. Although illustrated with only one secondary winding, it is to be understood that same may have more than one. These windings may be of any character such as for example, lagging windings, split windings, etc.

The phenomena with which we are here concerned arise by virtue of the existence of an end gap. Such end gaps are especially useful in preventing saturation which might occur in the vicinity of the secondary winding in the event the secondary winding was designed to carry a leading current. However, due to the improvement in wave shape, under certain circumstances, the secondary may carry lagging current. The invention is applicable to both types of secondaries.

There is shown a transformer 20, having a shell-like outer core 21 having bridging ends 22 and 23. The transformer is formed of two windings, a primary P and a secondary S both of which are mounted upon a central winding leg 24 and are spaced apart sufficient to clear the magnetic shunt 26 between the windings. The left hand end of the winding leg 24 matingly engages at 25 in the bridging end 22 with good magnetic contact and the right hand end of the winding leg 24 has been foreshortened to provide a space or air gap 27 at that point. There is a very small bridging projection 28 in the center of the end face of the winding leg which engages the opposite face of the gap 27 so as to support the central winding leg 24 in proper position within the shell core 21.

In the fabrication of this transformer 20 it is usual that the center winding leg 24 be punched out of the large plates forming the laminations of the core 21 so that there is exact fit at the juncture 25. The gaps 27 and 30 in the shunt are then shaved. The windings P and S are pre-wound, slipped over the ends of the winding leg 24 and the assembled winding leg is pressed home into the core. The connections are taken out of the cannister in which the transformer is disposed, with perhaps condensers and other electrical elements suitably connected, and the entire device is potted, i.e., covered with pitch, and sealed.

Returning now to the construction of the transformer 20, the magnetic shunt may be formed of extensions from the sides of the core 20 which face the sides of the winding leg, or, as in the case illustrated in FIG. 1, the sides of the core and the winding leg may be provided with short extensions 32 and 33 which are spaced apart sufficient to provide the gaps 30.

In FIG. 3, instead of the protuberance 28, the transformer 20 may have the central winding leg seated in a shallow recess formed in the bridging end, the recess in turn having a portion narrower than the width of the winding leg so that there are formed corner support notches 34 for the winding leg 24. The effect is the same as in FIG. 1.

Referring now to FIG. 2, there is shown the diagram of the circuit of the transformers of FIGS. 1 and 2. This, together with the transformer form no part of the invention but merely illustrate the difficulty which the invention overcomes. The circuit shows the transformer 20 being designated in the conventional manner and having the primary P and the secondary S connected end to end at the juncture 40. The primary P is connected across the line which is indicated by the terminals 41 and 42. The core 20 and the shunt 26 are designated by groups of lines in the conventional manner. In this instance the secondary S is intended to draw a leading current. There is shown a gaseous discharge device in the form of a fluorescent lighting tube 43 connected across both of the windings P and S by the left hand lead 44 which extends to the terminal 42 and the right hand lead 45 which extends to the right hand end of the secondary S and has a condenser C in series therein. This is an auto-trans-

former connection. The operation of the device is well known and consists of the ignition of the lamp 43 by virtue of the open circuit voltage developed across both windings followed by the protection of relatively large reactance whereby to limit the flow of current in the lamp. The circuit may be varied by the addition of other windings as previously mentioned herein and instead of the instant-start lamp illustrated, a pre-heat type of fluorescent lamp may be used.

In FIG. 4 I have shown the positive and negative cycles of a voltage wave which results from the phenomena heretofore discussed. The general configuration of the wave is that of a sine wave as indicated at 47 but, it will be seen that the great increase in rate of change of flux which occurs when the voltage is a maximum results in peaks 48 superimposed upon the sine wave 47. It has been found desirable to produce a current in the lamp 43 which is fairly flat topped in order to achieve maximum brilliance during the greatest part of the cycle. Obviously the current wave which would result by reason of the voltage wave of FIG. 4 would likewise be peaked and certainly not flat topped. Furthermore, as pointed out the peaks which are caused by the construction heretofore used also may produce pre-ignition in the pre-heat type of fluorescent lamp.

The invention as previously stated has as its principal object the elimination of the peak and the production instead of a relatively flat-topped wave. This is done by the elimination of the protuberance 28 at the right hand end of the winding leg 24 such that the great rate of change of flux is impossible. Furthermore, by providing such a protuberance at the magnetic shunt 26, there is provided a by-passing of flux at the magnetic shunt 26 which will automatically decrease the voltage developed in the secondary at the point of maximum voltage. This results in just the opposite of the phenomena described so that instead of the peak 48 as shown in FIG. 4 there is a dip as shown at 49 in FIG. 9. By suitable design the dip 49 may be modified to provide a relatively flat topped wave which is illustrated in FIG. 10.

I believe that this is caused by the same general principles which give rise to the peaking. The permeability of the protuberance at the shunt 26 is increased as the voltage increases, while the flux approaches zero, so that the flux tends to pass through these protuberances instead of through the end gap 27. This compresses the flux wave so that the rate of change as the flux wave passes through zero (point of maximum voltage) is considerably reduced. Obviously, with voltage being proportional to rate of change of flux, there will be no sharp peak at the voltage crest.

FIGS. 5, 6, 7 and 8 illustrate the forms which the invention may take. Thus, in FIG. 5 there is shown a transformer 50 whose construction is similar to that of the transformer 20 in FIG. 1 with certain important exceptions. The gap 27 in transformer 50 is unobstructed by reason of the elimination of the protuberance 28 and the winding leg 24 is supported by means of a protuberance 51 carried by each of the extensions 33 of the magnetic shunt 26. In order to eliminate end-wise play of the winding leg 24 the gaps 30 are slanted downwardly and towards the right, so that any tendency of the winding leg to pull away from the connection 25 will result merely in a tight wedging engagement of the extensions 32 with the protuberances 51.

In FIG. 6 there is shown a modified form of the invention. In this instance transformer 60 is provided with inwardly extending parts 53 which stop just short of the central winding leg 24. The central winding leg 24 is also provided with outwardly extending parts 54 which extend to just short of the inner edges of the core 21. The vertical facing surfaces of the extensions 53 and 54 are also spaced apart so that a relatively long air gap 55 is formed. This provides a large gap area, especially needed in the cases where S is to carry a lagging current. The facing

surfaces of the extension 53 are each provided with small protuberances 56 whose purpose is the same as the protuberance 51 of FIG. 5. In FIGS. 7 and 8 no provision is shown to prevent end wise movement of the central winding leg 24 and it is presumed that some expedient will be used to counter this movement during operation of the transformer. For example, the end gaps 27 may be filled with some non-magnetic substance such as fibre, paper or the like. In the case of the transformer 70 the outwardly extending portions 32 are each provided with a pair of protuberances 72 to produce the necessary effect. In the case of the transformer 80 the inwardly extending portions 33 are each provided with a single protuberance 82 also for the purpose set forth above. Obviously in each of the forms of FIGS. 5 through 8 there may be 15 one or more small protuberances used if desired, depending upon the results expected.

The wave shape which is produced in the current of the secondary S as a result of these constructions has been found to produce considerably better illumination than with a relatively peaked wave. The ratio of peak to 20 R.M.S. voltage can be made less than 1.414 with excellent results.

The constructional details of transformer 20 shown in FIG. 1 and the circuit thereof shown in FIG. 2 are known in the prior art. The dimensions of the examples of FIGS. 5 to 8 are of the same general proportion with the protuberances 51, 56, 72 and 82 of a practical size to maintain the gap spacing and firmly hold the respective winding legs 24 in place.

While I have shown and described specific examples of the invention as used in connection with gaseous discharge devices, it is pointed out that the device has much broader application. In many cases in which a square wave is desired, and where from the type of load electromagnetic means are appropriate, the invention may be applied. Likewise the constructions which have been shown and described by way of examples are capable of wide variation. The device may for example be constructed of L-shaped laminations arranged one opposite the other in which case there is no central winding leg. In this case, the windings are usually each split into halves and placed on opposite legs of the respective L's. The shunt between the secondary and the rest of the device may be a stack of laminations added, and may 45 have only one gap instead of two. Similar variations of structure are obviously possible.

In conclusion, it is desired to emphasize that the theory of operation of the invention has not been set forth by way of limitation but only for clarification. I desire to cover all the modifications of the invention construction as described, irrespective of the theory of operation, except of course as limited by the claims appended hereto.

What it is desired to claim by Letters Patent of the 55 United States, is:

1. An electromagnetic device serving at least one gaseous discharge device and adapted to ignite and thereafter regulate the operation of the same from a relatively low voltage source of A.C. voltage, including at 60 least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt 65 separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest.

the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest.

2. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, the said last mentioned gaps slanting inwardly toward the winding leg and end of the transformer having said end gap whereby any endwise movement of the central winding leg toward the said end gap will be resisted by the said protuberances.

3. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, there being an inward extension on each of the core sides adjacent the secondary winding, and an outward extension on each side of the central winding leg approaching but not meeting the said inward extensions whereby to form said shunt and said last mentioned gaps.

4. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through

the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, there being an inward extension on each of the core sides adjacent the secondary winding, and an outward extension on each side of the central winding leg approaching but not meeting the said inward extensions whereby to form said shunt and said last mentioned gaps, said protuberances being integral with a pair of extensions.

5. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, there being an inward extension on each of the core sides adjacent the secondary winding, and an outward extension on each side of the central winding leg approaching but not meeting the said inward extensions whereby to form said shunt and said last mentioned gaps with adjacent extensions being generally rectangular in configuration and having facing edges perpendicular to the central winding leg.

6. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, there being an inward extension on each

of the core sides adjacent the secondary winding, and an outward extension on each side of the central winding leg approaching but not meeting the said inward extensions whereby to form said shunt and said last mentioned gaps with adjacent extensions being generally rectangular in configuration and having facing edges perpendicular to the central winding leg with the protuberances between said facing edges.

7. An electromagnetic device serving at least one gaseous discharge device and adapted to ignite and thereafter regulate the operation of the same from a relatively low voltage source of A.C. voltage, including at least a primary winding and a secondary winding, the primary winding being connected with the source to be energized thereby, and physically separated from the secondary winding, the windings being connected in transformer relationship, and the gaseous discharge device being connected to the secondary so that the secondary current will flow through the discharge device, a shell-like core mounting said windings and including a central winding leg, the secondary winding being positioned at an end of the said winding leg within the shell-like core, the core including a bridging end member, the end of the winding leg mounting said secondary winding being slightly spaced from the bridging member and totally free therefrom to provide an end gap, a magnetic shunt separating the secondary winding from the remainder of the transformer and including an air gap on opposite sides of the central winding leg, at least one minute protuberance bridging each of the last-mentioned gaps for maintaining the spacing of the gaps and serving as a flux by-pass path at maximum open circuit voltage, whereby to flatten the voltage crest, there being an inward extension on each of the core sides adjacent the secondary winding, and an outward extension on each side of the central winding leg approaching but not meeting the said inward extensions whereby to form said shunt and said last mentioned gaps with adjacent extensions being generally rectangular in configuration and having facing edges perpendicular to the central winding leg and having ends terminating short of the core sides and central winding leg respectively whereby the gap formed thereby is of relatively great length and hence large area.

8. An electromagnetic device of the character described which is designed to provide substantially square wave of voltage to a gaseous discharge device which comprises, a rectangular shell core, a central winding leg matingly seated in the core and having an end thereof terminated just short of the inner face of an end of the core and not touching the same whereby to provide an end gap, a magnetic shunt spaced from the end gap to provide a winding window and extending between the sides of the shell core and the winding leg and including at least a non-magnetic gap, a source of A.C. voltage, a secondary winding disposed in the window, a primary winding on the winding leg opposite said secondary winding and being connected across said source to be energized thereby, a transformer connection between the windings whereby the secondary will provide a current when energized by the primary, a gaseous discharge device connected with the secondary winding, and a small bridging bead of magnetically conducting material rigidly engaged in said non-magnetic gap of said shunt.

9. A device as described in claim 8 in which the windings are connected in auto-transformer connection and the gaseous discharge device is connected across both windings.

10. A device as described in claim 8 in which the windings are connected in auto-transformer connection and the gaseous discharge device is connected across both windings and there is a condenser in series therewith.

11. A transformer providing a flattened voltage wave to a load, comprising a primary winding and a secondary winding connected in transformer relationship, a magnetic core having the windings mounted thereon, a com-

mon flux path for the flux of said windings in the core having an air gap therein to limit the flux density in the vicinity of the said secondary winding, and a saturable shunt between the windings, said shunt being saturated throughout substantially all of the output voltage wave of said transformer, except at the peak of said wave, and having relatively high permeability at said peak.

12. A transformer providing a flattened voltage wave to a load, comprising a primary winding and a secondary winding connected in transformer relationship, a magnetic core having the windings mounted thereon, a common flux path for the flux of said windings in the core having an air gap therein to limit the flux density in the vicinity of the said secondary winding, and a saturable shunt between the windings for diverting the primary magnetic flux during operation of the transformer, said shunt including a highly constricted portion completely saturated at zero open circuit secondary voltage, and having maximum permeability at peak open circuit secondary voltage.

13. A transformer providing a flattened signal to a load, comprising a magnetic core, a primary winding connected to an A.C. source, a secondary winding in transformer relationship to the primary winding, the windings mounted on said core with a common flux path, the load being connected with at least the secondary winding, a non-magnetic gap in the core and in the said common flux path, a shunt between the windings, and means rendering the shunt highly saturable throughout the entire cycle of the output voltage except at peak amplitude.

14. A transformer providing a flattened signal to a load, comprising a magnetic core, a primary winding connected to an A.C. source, a secondary winding in transformer relationship to the primary winding, the windings mounted on said core with a common flux path, the load being connected with at least the secondary winding, a non-magnetic gap in the core and in the said common flux path, a shunt between the windings, at least a part of the shunt having cross-sectional area very small relative to the remainder of the flux paths of the said core whereby said shunt is saturable during operation except at peak open circuit voltage.

15. A transformer providing a flattened signal to a load, comprising a magnetic core, a primary winding connected to an A.C. source, a secondary winding in transformer relationship to the primary winding, the windings mounted on said core with a common flux path, the load being connected with at least the secondary winding, a non-magnetic gap in the core and in the said common flux path, a shunt between the windings, at least a part of the

shunt having cross-sectional area very small relative to the remainder of the flux paths of the said core whereby said shunt is saturable during operation except at peak open circuit voltage, at least a part of the said shunt being of a magnetic material having a relatively low saturable flux density.

16. A transformer providing a flattened signal to a load, comprising a magnetic core, a primary winding connected to an A.C. source, a secondary winding in transformer relationship to the primary winding, the windings mounted on said core with a common flux path, the load being connected with at least the secondary winding, a non-magnetic gap in the core and in the said common flux path, a shunt between the windings, at least a part of the shunt having cross-sectional area very small relative to the remainder of the flux paths of the said core whereby said shunt is saturable during operation except at peak open circuit voltage, said shunt including at least a non-magnetic gap having a small bridging protuberance therein, whereby the protuberance is saturated and of substantially the permeability of the remainder of the gap except at peak open circuit voltage.

17. A high reactance transformer comprising a magnetic core having a winding leg member and a multileg yoke member, one end leg of said yoke member abutting one end of said winding leg member and the other end leg of said yoke member defining a series air gap with the other end of said winding leg member, a primary winding and a secondary winding in spaced relation on said winding leg member, said yoke member having a leakage leg extending intermediate said primary and secondary winding toward said winding leg member and defining a shunt air gap with said winding leg member, and a magnetic bridge across the shunt air gap between said leakage leg and said winding leg, said bridge maintaining the spacing and position of both said series and shunt air gaps and reducing the open circuit peak voltage of said secondary winding.

18. A high reactance transformer of claim 17 wherein the magnetic bridge comprises a portion of the leakage leg abutting said winding leg member.
